Primary Examiner — T Chase Nelson(74) *Attorney, Agent, or Firm* — Marshall A. Lerner; Marvin H. Kleinberg; Kleinberg & Lerner, LLP**CLAIM**

The ornamental design for a shoe outsole bottom, as shown and described.

DESCRIPTION

FIG. 1 is a perspective view of a shoe outsole bottom in accordance with my new design.

FIG. 2 is a bottom plan view thereof;

FIG. 3 is a right side view thereof;

FIG. 4 is a left side view thereof;

FIG. 5 is a front elevation view thereof;

FIG. 6 is a rear elevation view thereof; and,

FIG. 7 is a top plan view thereof.

The broken lines shown in the drawings represent portions of the shoe upper, midsole periphery and outsole bottom that form no part of the claimed design.
